HYDROTHERAPY CABINET

Walter H. Bohnenblust, Kansas City, Kans.

Application March 23, 1959, Serial No. 55,104

Term of patent 3½ years

(Cl. D83—1)

*Fig. 4.**Fig. 5.*

Fig. 1 is a top plan view of a hydrotherapy cabinet, showing my new design.

Fig. 2 is a rear elevational view thereof.

Fig. 3 is an elevational view of one end thereof.

Fig. 4 is a front elevational view with the hood open;

Fig. 5 is a perspective view of the opposite end of the hydrotherapy cabinet; and

Fig. 6 is a fragmentary transverse cross sectional view thereof taken on line 6—6 of Fig. 2.

The heavy vertical shading is for the purpose of showing contrasting color.

I claim:

The ornamental design for a hydrotherapy cabinet, as shown and described.
